UNITED STATES PATENT OFFICE.

ROBERT E. BALLOW, OF ESTANCIA, NEW MEXICO.

CARBURETOR.

Application filed May 10, 1924. Serial No. 712,305.

To all whom it may concern:

Be it known that I, ROBERT E. BALLOW, a citizen of the United States, residing at Estancia, in the county of Torrence and State of New Mexico, have invented certain new and useful Improvements in Carburetors, of which the following is a specification.

This invention relates generally to the art of fuel atomizers for internal combustion engines, and has more particular reference to what is known in the art as a carburetor, the primary object of the invention residing in the provision of such a device wherein the gasoline or other fuel is completely atomized before the same passes to the intake manifold of the engine, thereby resulting in the economical and efficient operation of the engine.

20 An additional object of my invention is to provide a carburetor, wherein the fuel is subjected to a whirling action under the influence of the engine suction for producing said complete atomization of the fuel.

25 A still further and important object of the invention is to provide a carburetor wherein a relatively great amount of air is taken into the manifold together with a relatively small amount of fuel, but due to the fact that complete mixture of these elements is accomplished, a satisfactory combustible mixture is produced.

30 Another object is to provide means for absolutely drawing the fuel from the float chamber of the carburetor and subjecting the same to a whirling action before the fuel passes to the engine cylinders.

35 Another object resides in the provision of means for automatically subjecting the fuel to a whirling action, and this due to the suction created in the engine cylinders.

40 A final and salient object is to provide a carburetor that is relatively simple of construction and efficient in operation and one that may be entirely disassembled by unskilled persons for repair or renewal purposes.

45 With the foregoing and other objects in view as the nature of the invention will be better understood, the same comprises the novel form, combination and arrangement of parts hereinafter more fully described, shown in the accompanying drawings and claimed.

In the drawings wherein like reference characters indicate corresponding parts throughout the different views:

Figure 1 is a detailed vertical sectional view of a carburetor constructed in accordance with the present invention.

60 Figures 2 and 3 are detailed transverse sectional views taken substantially upon the lines 2—2 and 3—3 of Figure 1 and looking in a downward direction.

Figure 4 is a side elevational view of the 65 fuel whirling or operating device per se, that constitutes a major element of the present carburetor construction, and

Figure 5 is an enlarged perspective view 70 of a member that is associated with the lower end of said fuel whirling or operating device, the use of which results in the effective feeding of the fuel into said whirling or operating device.

75 Now, having particular reference to the drawings, my novel carburetor among other elements constitutes the provision of a fuel bowl 5, that is open at its upper end, and formed at its bottom wall with a collared opening 6. This bowl 5 is further formed at one side of said collared opening with a threaded opening 7, within which is threaded a nipple 8, the inner end of which is formed with an extension 9, to the upper end of which is suitably pivoted a ring shaped float 10. This member 8 is maintained within said threaded openings through the medium of a jam nut 11 and set screw 12, the lower end of said nipple being 80 formed with an internally screw threaded socket for the threaded reception of one arm of an elbow fitting 13, the other end of which is adapted to be attached to the gasoline feed line.

85 Extending through said nipple 8 is a relatively restricted fuel passage-way 14, the upper end of which is bevelled to provide a valve seat, with which cooperates a needle valve 15, that is actuated to opened and closed positions through the falling and rising of said ring float 10.

90 Disposed within the central collared opening 6 of the fuel bowl 5 is a pendent hollow nipple 16, that is formed upon the lower end of a circular shaped cylinder 17. The nipple 16 of this cylinder 17 is exteriorly screw threaded whereby the same may be maintained within the bottom wall opening of the

fuel bowl 5, through the medium of a jam nut 18. The fuel within the bowl 5 enters said cylinder 17 through the medium of a series of passage-ways 19 formed in the 5 lower end thereof, and for the purpose of allowing said cylinder to be drained whenever necessary, there is threaded within said nipple a plug 20, the inner end of which is pointed for positioning upon a valve seat 21 10 at the inner end of said nipple, said nipple communicating with the cylinder through the medium of a passage-way 22. This plug 20 is formed with a bore 23 that extends inwardly to a point adjacent the pointed end 15 of the plug, the inner end of said bore having communication with the interior of the nipple through the medium of a right-angularly extending passage-way 24, it being obvious that a slight unscrewing of this 20 plug will allow the fuel within the cylinder to pass into the nipple through the passage 22, and thence inwardly through the passage 24, and then through the bore 23 of said nipple 20.

25 The upper end of the cylinder 17 is internally screw threaded for receiving the lower externally screw threaded end of a pipe 25, that is formed centrally of and depends from the fuel bowl lid 26. Formed upon the 30 external surface of said lid 26 and at its marginal edge is an upstanding circular collar 27 that is externally screw threaded at its upper end, whereby a similar shaped collar 28 may be secured thereto, through the medium of a cushioning sleeve or collar 29. This collar 28 is an integral part of a T-fitting 30, that includes a rectangular pipe 31 that has communication with said collar 28 through the medium of a circular restricted passage-way 32.

40 Previous to the threading of the lid carrying pipe 25 into the cylinder 17 there is threaded within the lower end of said pipe a sleeve 32, the lower end of which is formed internally with a bearing raise-way 33. The upper end of the lid carrying pipe 25 communicates with the interior of the lid carrying collar 27 through an opening in the lid, and inwardly of the upper end of this pipe, the same is internally threaded for the reception of a threaded sleeve 34, that is also formed at its upper end with an internal ball bearing raise-way 35.

55 Extending downwardly through said pipe 25 and disposed centrally therein is a hollow relatively elongated stem 36 of a hollow fuel whirling member 37 with the interior of which said hollow stem 36 communicates.

60 At the upper end of this stem 36, the same is threaded for the threaded reception of a bearing collar 38 between which and the last mentioned raise-way 35 are suitable bearings 39. The lower end of the stem 36 is threaded for the reception of a sheet metal sleeve 40, spaced from the inner end of

which is formed a raise-way, between which and the raise-way 33 are ball bearings 41, that cooperate with the other bearings 39 for allowing a free rotation of the stem within the cylinder 17 and pipe 25.

70 The lower end of the sheet metal sleeve 40 is formed upon diametrically opposite points with inwardly extending dished blades 42, the angle of which is such as to scoop up the fuel within the cylinders 17 during the rotation of the stem 36 for thereby insuring the positive entrance of the fuel into said stem.

75 The hollow fuel whirling member 37 is formed with radial dished blades or fins 43, as well as radially extending diametrically disposed hollow chambers 44 that communicate with the interior of said hollow member 37. These chambers 44 are formed upon their top sides with threaded openings, within which are threaded relatively small fuel outlets 45.

80 The lid carrying collar 27 is formed at a point beneath the whirling member 37 with air inlet openings 46, and it will be obvious that when the carburetor is installed, the suction of the engine cylinders will result in the intake of air through the openings 46, which air impinging upon the blades 43 will 85 cause the ratchet rotation of the whirling device for drawing the fuel upwardly through the stem 36, and the same will discharge from the outlets 45 in an operating or whirling action, which will permit of a thorough 90 mixture of the air and fuel in the collar 28 of the T-shaped fitting.

95 One end of the horizontal pipe portion 31 of the fitting 30 is formed with the usual manifold attachment flange 47, and within this end of said horizontal pipe 31 is the usual throttle valve 48 operable through the medium of an actuating arm 49 by the usual accelerator mechanism employed. The opposite end of said horizontal pipe 31 is 100 equipped with an air control valve 50 operable in any manner desirable.

105 Within the restricted passage-way 32 between the collar 28 and horizontal pipe 31 is a valve 51, operable through the medium of a stem 52 whereby the amount of mixture 110 passing from the carburetor may be manually controlled independently of the throttle valve 48.

115 The hollow member 37 of the fuel whirling device may be and preferably is formed with a threaded opening for the reception 120 of a plug 53 whereby the same may be cleaned whenever necessary.

125 It will thus be seen that I have provided a highly novel, efficient and durable form of carburetor, and one the use of which will result in economical and efficient use of fuels, and wherein the cheaper grades of gasoline or even kerosene may be employed due to the fact that the fuel is entirely atom- 130

ized before passing to the engine cylinders.

Minor changes may be made in the invention without departing from the spirit and scope of the appended claim.

5 Having thus described my invention, what I claim as new, and desire to secure by Letters-Patent, is:

In a carburetor, a fuel bowl, a pipe depending from the top of the fuel bowl and 10 terminating a distance from the bottom thereof, a cylinder rising from the bottom of the bowl and communicating with the pipe, said cylinder merging at its bottom end into a nipple which extends through an 15 opening provided in the bottom of the bowl, drain means at the bottom end of the nipple, said cylinder provided with openings adjacent the bottom of the fuel bowl for receiving fuel therefrom, a hollow stem rotatable mounted within the pipe and the cyl- 20

inder and having one end terminating within said cylinder and the other end terminating above the fuel bowl, bearings for the stem in both the pipe and cylinder, means on the end of the stem within the cylinder 25 for forcing gasoline from the cylinder upwardly through the hollow stem, a mixing chamber above the fuel bowl and provided with air inlet openings, the upper end of said hollow stem terminating within the 30 mixing chamber above the openings thereof, a head on the upper end of the hollow stem, fuel outlets projecting upwardly from the head, and fins radiating from the head so that air being thrust through the openings 35 of the mixing chamber will impinge against said fins for causing the rotation of the stem.

In testimony whereof I affix my signature.

ROBERT E. BALLOW.
